LOCK-STITCH SEWING MACHINE

Ewald Kühn, Weissenfels, Germany, assignor to
the firm Nollesche Werke, Komm. Ges., Weiss-
enfels, Germany

Application September 2, 1937, Serial No. 162,215
In Germany June 8, 1935

14 Claims. (CL 112—36)

The present invention relates to a lock-stitch sewing machine which is equipped with a horn which contains the thread feeder and the whirl and serves as a support for the work piece and is principally intended for the sewing of boots and shoes. It has as its object to simplify the construction of such machines, to accelerate their operation and to reduce the danger of the premature wearing out of the movable parts.

10 In the case of the known machines which are equipped with a horn, the parts that lie within the horn are coupled with their drive which lies outside the horn by means of intermediate gearing which have large dimensions and, consequently, a great weight and therefore, owing to their inertia resistances and frictional resistances, have a disturbing influence on the running and, chiefly, on the starting and stopping of the machine. According to my invention, this disadvantage is 15 avoided by virtue of the fact that an intermediate shaft, which is connected to the whirl-driving shaft that lies within the horn, is led past the bearing places for the rotary movement of the horn and through the whole horn-carrier and 20 comes into driving connection only beneath the horn-carrier with a pinion which is arranged so as to be rotatable on the horn-carrier and concentrically with its axle and on which the drive which lies outside the horn works directly. 25

30 In this way, there is produced considerable reduction of the weight, of the dimensions and of the frictional and inertia resistances of the intermediate means provided between the whirl-driving shaft and its drive that lies outside the horn, so 35 that the machine can be started and stopped more easily and rapidly than hitherto and is thus especially suitable for rapid running. Furthermore, it is in this way rendered possible to give the horn a considerably slenderer shape than has been the 40 case in the known constructions, so that the putting on and taking off of high-legged boots is facilitated. Finally, owing to the novel passing of the intermediate shaft through the horn-carrier, there 45 is also obtained the advantage that the rod guide, which is provided in the horn-carrier and surrounds the thread, can be heated more effectively than hitherto. The rod guide is exposed in an 50 advantageous manner for the direct placing of the heating device thereon, so that the guide can be heated directly and a very short heating time is necessary and it is possible to put the machine rapidly into working order.

55 Advantageously, there are provided as operating linkages for the thread-feeder and the thread clamp two slide rods which are slidably mounted

in longitudinal grooves that are arranged in the guide forming the axle of the horn. These slide rods have, as compared with the known tubes that are concentric with the axle of the horn, a smaller weight, smaller mass resistances and fewer large frictional surfaces in their guide, so that, in this way, the rapid running of the machine is favourably influenced still further. In addition, they leave a greater part of the rod guide free for the direct action of the heating device.

10 Ordinarily, the lock-stitch machines of the kind that come into consideration here are equipped for the bottom thread with a thread brake which co-operates with the thread-feeder roller that is arranged in the horn and which is controlled in 15 accordance with the sewing operation. In this case, there is then provided between the yarn stock roll and the thread brake a special auxiliary take-up which is to keep the thread taut on its 20 guide rollers. This auxiliary take-up does not work reliably enough at a high sewing speed and frequently leads to unallowably great straining of the thread on account of the spring that is necessary for its operation. Consequently, according to the invention, the pivot pin of the rocking lever 25 which acts on the slide rod of the thread-feeder roller is mounted on an arm which imparts to the rocking lever of the thread-feeder roller an additional movement which takes the place of the work of the auxiliary take-up which is otherwise 30 provided. The control of the crank arm is advantageously effected with the aid of a cam plate which is driven from the machine and which may be provided on the shaft which controls the coupling gearing. The crank arm or the shaft that 35 carries it is advantageously kept in yielding contact with the cam plate by a spring, so that the shaft can yield on any change that may occur in the thickness of the work piece or on the occurrence of other irregularities in the work piece. 40 The thread loop which is otherwise yieldingly held by an auxiliary take-up is therefore now received by the thread-feeder roller itself which is given through the coupling gear, by the crank arm that is controlled by the crank, an additional 45 movement which approximately corresponds to the movement of the needle. In this way, the result is obtained that, during the sewing operation, the thread-feeder roller always necessarily releases as much thread as the needle requires 50 for its working.

Further features of the invention are involved in the drive of the needle bar and of the shuttle, which features render these parts suitable for a running of the machine that is as rapid as possible.

For the purpose of raising and lowering the needle bar, there is provided, according to the invention, a toggle-lever gearing which receives its drive from a uniformly rotating crank. The toggle-lever movement of this gearing is of especial advantage because, on account of the passage of the levers through their stretched position, which passage is effected in the bottom position of the needle bar, the needle is given a comparatively long stoppage in its bottom end position, so that the time for insertion of the thread into the hook of the needle, which time is otherwise short in the case of rapidly running machines, is extended. In addition, such a gearing involves the advantage that, even in the case of thick strong leather material, the forces that act against the needle are transmitted to the parts of the drive only to an inconsiderable extent. For the purpose of increasing also the period of stoppage of the needle 10 in its top position, the rocking lever of the toggle-lever gearing, which rocking lever comes into engagement with the driving crank, may be equipped with an arcuate slot which runs concentrically with the axle of the driving crank for a part of its length that corresponds to about the highest position of the needle, so that the crank pin does not produce any movement of the gearing when in the part concerned of its path.

The movement of the shuttle is, as a rule, effected in the case of the known machines by eccentric cams or other reciprocating parts which, on the change of the direction of movement, require great accelerating forces and cause sudden strains in the gearing. These disadvantages are especially in evidence in the case of rapidly running machines. For the purpose of remedying this defect also, there is employed, according to the invention, for driving the shuttle actuator, a uniformly rotating crank which acts on an arc crank which is connected to the stand of the machine by a link and carries out, with its thrust roller, a movement which runs somewhat as an 8-shaped coupled curve loop and which is transmitted to the shaft of the shuttle picker by the engagement of the follower in the appropriately shaped cam groove in a slide link that lies with its axis of rotation in the larger part of the coupled curve loop. The passage of the follower through the crossing position of the curved path 15 then, notwithstanding the fact that its drive is derived from the uniformly rotating crank produces a sufficiently large temporary stoppage of the shuttle and renders possible a faultless adaptation of the movement of the shuttle to the movement of the other working parts of the machine.

The subject matter of the invention is represented by examples of embodiment in the accompanying drawings, of which

Fig. 1 is a side elevation of the machine;
60 Fig. 2 is a partial front elevation and

Figs. 3 and 4 are two side elevations of the top part of the machine;

Figs. 5 and 6 are respectively a rear elevation and a front elevation of the drive of the shuttle;
65 Fig. 7 is a section through the horn and the saddle mounting of the horn;

Figs. 8 and 9 are respectively a front elevation and side elevation of the driving parts for the thread feeder and the thread brake; parts of each 70 figure being shown in section;

Fig. 10 is a plan of the driving parts for the thread feeder;

Figs. 11 to 13 are respectively a front elevation, a plan partly in section and a longitudinal section 75 of the casing of the shuttle; and

Figs. 14 to 19 show two further embodiments of the driving parts for the thread feeder.

The machine represented in the drawings is driven by an electromotor, the belt pulleys 87 of which are connected by belts (not shown), with 5 the counter-pulleys 88 on the upper shaft 2 that is mounted in the top part 1 of the machine. The driving of the parts working in the top part 1—namely, the needle bar, the feed point, the presser foot bar and the shuttle—is effected from the 10 upper shaft 2. Furthermore, the upper shaft 2 is coupled by a bevel-wheel gearing 89 with the vertical intermediate shaft 90 which is, in turn, connected with the shaft 107 (Fig. 7) through a corresponding bevel-wheel gearing. The drive of the 15 parts working in the horn 133 is derived from this shaft 107. The crank plate 3, which is fixed on the upper shaft 2, engages, by means of its crank pin 4, in the arcuate slot 5 of a rocking lever 6 which is rockably mounted on the axle 1. 20 The rocking lever 6 is connected by the intermediate member 9 and the bolts 8 and 10 with a further rocking lever 11 which is mounted on the stationary bolt 12 and carries a rotatable sliding block 13 on its free end. The flat sliding surfaces of the block 13 engage in a corresponding groove 14 in the needle bar 15, the bottom end of which has a longitudinal slot 16 and a bore in which the needle 17 is fixed with aid of the binding screw 18. The needle bar 15 is carried in the 30 bearings 19 and 20 in the upper part of the machine so as to be slidable in the vertical direction.

The rocking movements of the lever 6, which are produced by the rotating crank pin 4, are transmitted by the intermediate member 9 to the 35 rocking lever 11 which, acting through the sliding block 13, effects the up and down movement of the needle bar 15 which is secured against rotation. During the passage of the hinge bolt 8 through the straight line connecting the bolts 7 and 10, there 40 is produced the temporary stoppage of the needle 17 in its lowest position, which stoppage is necessary for the introduction of the bottom thread into the hook of the needle.

The arcuate slot 5 in the rocking lever 6, which 45 slot receives the crank pin 4, is formed in such a manner that its part which corresponds to the upper position of the needle bar 15 runs concentrically with the shaft 2. Consequently, the crank pin 4 does not impart any rotary movement 50 to the rocking lever 6 during a definite part of its path, so that the needle is given a comparatively long stoppage in the top end position, with the result that the pulling of the thread loop into the work piece is favoured.

The driving of the feed is effected from the two steel cam plates 21 and 22 (Fig. 3) which are mounted on the upper shaft 2 and which act on the bell-crank lever 38 (Figs. 3 and 4). This bell-crank lever 38 is rockably mounted on the 60 axle 7 on the upper part of the machine and carries on its pins 31 and 34 the rotatable rollers 32 and 33, of which the roller 32 runs on the cam plate 22 and the roller 33 runs on the cam plate 21. Since the plate 21 represents the counter- 65 cam to the plate 22, the bell-crank lever 38 is, on the rotation of the upper shaft 2, positively driven in accordance with the shapes of the cams. Rigidly connected with the bell-crank lever 38 is the arm 35 (Fig. 4) which has an arcuate slide 70 link 36 on its free end. The sliding block 37, which is displaceable in this arcuate slide link 36, is connected by the hinge bolt 38, the intermediate member 39 and the bolt 40 to the forked head 41 (Fig. 3) of the rocking lever 42 which 75

is mounted on the stationary pin 47. From the pin 43 on the head piece 41 an intermediate member 44 leads to the pin 45 on the lever 46, the pivot pin 48 of which is mounted on the end 5 of the lever 49 which is fixed on the axle 103 that is mounted in the body 1 of the machine. The bottom end 46' of the lever 46 is hinged by the pin 50 to the intermediate member 51, the free end 52 of which surrounds a cylindrical projection 10 on the feed lever 53. This feed lever 53 is formed with slots 54 and 55 which cooperate with pins 56 and 57 on the presser foot bar 58 which is designed to be raised and lowered. The feed-point holder 59 is hinged to the pin 60 of the feed lever 53, carries the feed point 61 and is pulled to the projection 63 on the feed lever by the spring 62. On the transmission of the movements of the bell-crank lever 38, which movements are caused by the cam plates 21 15 and 22, to the feed point 61, the parts 44, 46 and 49 form a hinged quadrangle which, on the raising and lowering of the presser foot bar 58, carries the pin 50 parallel to the direction of movements of the presser foot bar, so that, even at different 20 vertical positions, the feed point keeps its lateral position in relation to the presser foot bar.

For the purpose of shifting the feed point, the sliding block can be displaced in the arcuate slide link 36, at the centre of curvature of which the pin 40 lies. In this way, the effective length of the lever 35 which rocks about the axle 7 and, consequently, the path of the feed point 61 also are altered. For this purpose, there is hinged to the pin 64 of the intermediate member 39 an intermediate member or link 65 which is connected by the pin 66 with the adjusting lever 67 that is rockable about the pin 12. The hinge bolt 70 of the lever 67 carries a guide 69 in which rests the set screw 68 which is provided with a hand wheel 71. The free end of the set screw 68 engages in the small circular member 13 which is mounted in the body 1 of the machine. The rotation of the screw 68 with the aid of the hand wheel 71 produces a rocking of the lever 67 about the pin 12 and, through the intermediate lever 65, a corresponding rocking of the intermediate member 39, the block 37 of which is, in this way displaced in the arcuate slide link 36. The parts 65, 39 and 40 are pivotally interconnected in 50 square or rectangular outline which serves for guiding the sliding block 37 in its particular setting in relation to the lever 35.

The shuttle is, in the case of the machine represented in the drawings, driven from a uniformly 55 rotating crank 74 on the upper shaft 2. The crank pin 74 is embraced by a three-armed crank 75 which is connected by the bolt 76 with a link 77 that rocks about the stationary bolt 78. The shaft 79 of the shuttle picker is mounted in the upper part of the machine and carries a slide link 80, in the cam groove 81 (Fig. 5) of which the follower 82 of the arc crank 75 engages. Owing to this arrangement, the follower 82 of the arc crank 75 describes, on the rotation of the 60 crank pin 74, a somewhat 8-shaped path, the axis of rotation of the slide link 80 or of the shaft 79 of the picker lying at the centre of the larger loop of the 8. The slide link is thus given an interrupted rotational movement by the crank pin 65 that rotates always in the same direction, which movement is transmitted by the shaft 79 to the 70 shuttle. The 8-shaped looped path of the follower 82 causes a comparatively long stoppage of the shuttle during this rotation, so that the movement 75 of the shuttle and the movements of the remain-

ing parts which serve for forming the stitches can be favourably adapted to each other. In addition owing to the derivation of the movement of the shuttle from the uniformly rotating crank pin with the aid of the coupling gearing, the great accelerations and sudden strains of the driving parts, which occur in other shuttle drives, are avoided, so that the shuttle drive works considerably more steadily and is especially suitable for rapid running and is less exposed to the danger of 10 breakages of gearing and other disturbances.

The end of the shaft 79 remote from the slide link 80 has a splined connection at 83 with the hub of a bevel wheel 84. Permanently engaging with the bevel wheel 84 is the bevel wheel 85 15 which is rigidly connected by an intermediate shaft 87 with the shuttle picker 86. Owing to the arrangement of the longitudinal grooves 88 on the shaft 79 and the corresponding formation of the bevel wheel 84, this bevel wheel can be displaced together with the casing of the looper transversely to the direction of sewing and out of reach of the needle, as will hereinafter be more fully described.

The raising and lowering of the presser foot 91 25 is effected by the lever 49 which is fixed on the axle 103 and on the pin 48 of which there is fitted a sliding block 104 which engages in a corresponding groove in the presser-foot bar 58. The helical spring 92, which is provided on the axle 30 103, tends to rock the lever 49 in the direction of lowering the presser-foot bar 58. For the purpose of raising the presser-foot bar in opposition to the action of the spring 92, there is employed the lever 102 (Fig. 3) which is fixed to the axle 35 103 and which carries at its top end a clamping segment 93. The cam 98 on the upper shaft 2, on being rotated, rocks the lever 96 which carries the roller 97 and from which the fixed connection between the levers 101 and 102 is effected through 40 the clamping jaws 94. The roller 99, which runs on the cam 100, then causes an always equal lifting of the presser foot, even in the case of different thicknesses of leather, by the rotation of the axle 103 and the rocking of the lever 49. When 45 the machine is at rest, the presser foot may be raised by a special lever 105 which is to be operated for example by a treadle.

For the purpose of driving the whirl of the 50 thread feeder and the thread brake, there is mounted in the stand 115 of the machine a horizontal shaft 107 which is driven from the machine through an intermediate shaft with suitable bevel-wheel gears.

The drive of the whirl is effected with the aid of 55 the bevel wheels 163 and 164 that are driven by the shaft 107. The bevel wheel 164 is rigidly connected with the spur wheel 165 which engages in a further spur wheel 166 which surrounds the rod guide 125 like a socket and is arranged beneath the horn-carrier 132 and which, in its turn, meshes with the spur wheel 167 that is fixed on the intermediate shaft 168. This intermediate shaft 168 is passed through the whole horn-carrier 132 eccentrically to the axis of rotation of the horn and is connected by a universal joint 169 with the shaft 170 which drives the whirl in the known manner.

The drive of the thread feeder is derived from 60 the shaft 107 (Figs. 7 to 10) in the following 70 manner:

The crank pin 109 on the crank bush 108, which is rigidly arranged on the end of the shaft 107, is embraced by a coupling 110 which, at the other end, is hinged by the pin 111 to the rocking lever 75

112 that is mounted on the pin 113. The pin 113 is carried by an adjusting member 114 which is adjustable on the stand 115 of the machine with the aid of the screws 116 and the slots 117. The 5 roller 119, which is mounted on the pin 118 of the coupling 110 engages in the slot 120 in a rocking lever 121, the pivot pin 122 of which is mounted on an arm 123 which is rigidly arranged in the stand 115 of the machine. The end of the rocking lever 121 which projects beyond the slot 120 carries a rotatable sliding block 124 which engages in the groove in a socket ring 126. The socket ring 126 is slidably fitted on the vertical rod guide 125 and is connected to the slide rod 127 by means 10 of screws 128, the upper end of which slide rod, that carries the thread-feeder roller 129, projects into the horn 133.

The horn 133 is connected to the horn-carrier 132 which rests on ball bearings so as to be easily 20 rotatable in the bearing 131 of the stand 115 of the machine. In the horn-carrier 132 there is also fixed at 134 the rod guide 125 which is provided with a groove 125' (Fig. 10) for receiving the slide rod 127 and takes part in the rotation of 25 the horn and of the horn-carrier. The sleeve 130, which is put on the upper end of the rod guide 125 surrounds and guides the slide rod 127. The stroke of the slide rod 127 and, consequently, of the thread-feeder roller 129 can be altered by 30 shifting the adjusting member 114 that carries the pivot pin 113 for the rocking lever 112. In this way, there are altered the length of the curve described by the pin 118, the stroke of the lever 121 and, consequently, also the path traversed by 35 the thread-feeder roller 129.

Above the thread-feeder roller 129, there is mounted so as to be stationarily rotatable in the horn 133 a clamp roller 142 on which a clamp slide 143 bears under the action of the spring 145 40 that is adjustable by the screw 146. The slide 143 slides in the guide 144 which receives the spring 145 and the screw 146 and which is hingedly mounted at 147 in the horn 133. For the purpose of raising the slide 143, there is employed 45 the slide rod 157 which is slidably mounted in the groove 125" (Fig. 10) in the rod guide 125 and the top projection 157' of which engages below the clamp slide 143 and the bottom end of which is connected to the socket ring 156 that likewise slides 50 on the rod guide 125. The slide rods 157 and 127 are, on their external surface, rounded in accordance with the bore of the socket rings 126, 156 and the guiding sleeve 130.

The drive of the slide rod 157 is derived from 55 the cam plate 148 that is mounted on the crank bush 108 of the horizontal shaft 107. For this purpose, there is provided in the extension 149 of the bearing 131 of the horn-carrier a pin 159 which carries a lever that consists of the arms 60 151 and 151'. The lever arm 151, which carries a roller 152 on its pin 153, is kept in permanent contact with the cam 148 by the spring 154. The other lever arm 151' carries a sliding block 155 which engages in the groove in the socket ring 65 156 which is connected to the slide rod 157, so that the rockings of the lever 151 and 151', which are produced on the rotation of the cam 148, effect a raising and lowering of the slide rod 157, the end 157' of which then, in turn, lifts the clamp 70 slide 143, in opposition to the action of the spring 145, for the purpose of releasing the thread. The vertical position of the projection 157' can be varied within certain limits by means of the screw 158 that is provided between the lever arms 151 and 151'.

The fitting in and taking out of the rods 127 and 157 is facilitated by the hinge-like mounting of the clamp-slide guide 144. Thus, when the guide 144 is folded upwards about the hinge 147, then, after detaching the socket rings and the roller 142, the rods 127 and 157 can be readily pulled upwards out of the horn. After fitting these parts in, the guide 144 is again folded back downwards and is locked in this position.

The thread coming from the stock of yarn runs 10 by way of a thread brake 135 into the wax pot 136 and, from there, passes over the guide roller 137 to the pitch-stripper 138. From there, it is passed by way of an auxiliary take-up and through the bore 139 in the rod guide 125 into the horn 133. 15 The auxiliary take-up consists of a lever 160 which is rockable about the pin 159 and through a hole 161 in which the thread passes. The lever 160 is operated by a spring 162 in such a manner that the thread always remains drawn taut and lies on the parts 135 to 138. The tension of the spring 162 is smaller than that of the thread brake 135. On its way through the bore 139, the thread is kept at a uniform temperature by an annular heating member 163 which surrounds a jacketing member 164 of the rod guide. It then runs over the clamp roller 142 and the thread-feeder roller 129 and vertically upwards and out through the thread feeder to the tip of the horn. The co-operation of the thread-feeder roller 129, which is controlled by the slide rod 127, and the clamping device 142—146, which is raised by the slide rod 157 gives a reliable measuring and feeding of the thread.

In the case of lock-stitch sewing machines, the shuttle is ordinarily arranged as closely as possible 35 to the needle for the purpose of obtaining a faultless seam. In this way the free space between the tip of the horn and the head piece of the machine is greatly restricted, so that the putting of work pieces on the horn involves difficulties, especially 40 in the sewing of long-legged boots. This disadvantage is avoided by the displaceable mounting of the casing of the shuttle as illustrated in Figs. 11 to 13. Here, the upper part of the machine carries the casing 193 of the shuttle with the shuttle 194 displaceably in a carriage guide 192. Arranged rotatably on a pin 195, which is fixed in the upper part of the machine, is the adjusting lever 196 on which a pawl lever 198 is mounted so as to be rotatable about the pin 197. A compression spring 199 presses the pawl 200 against a stop piece 201 which is adjustable on the upper part 1 of the machine with the aid of the screw 202. The lever 196 has, in an extension 203, a slot 203' which serves for guiding the pin 204 which 50 is fixed to the casing 193 of the shuttle.

Now, if the shuttle is to be brought into the working position, the pawl lever 198 is moved 55 downwards. In this way, the locking of the lever 196 is released, because the pawl 200 is moved away from the face 201' of the stop 201. Thereupon, the lever 196/198 is rotated round the pin 195 into the position shown in dot-and-dash lines (Fig. 12), its extension 203 bringing the casing of 60 the shuttle forward, through the pin 204 into the dot-and-dash position in which the set screw 205 meets the bolt 206 in the head piece. The position of the tip of the shuttle in relation to the needle can be adjusted accurately with the aid of the 65 screw 205. Now, if the pawl lever 198 is released in this position, the pawl 200 is brought by the compression spring 199 behind the face 201' of the stop 201 and the shuttle is fixed because, on the one hand, the set screw rests on the bolt 206 70 75

and, on the other hand, the pawl 200 rests on the stop 201".

The housing of the spool is fixed in the casing of the shuttle by a holding finger 208 which is rockably mounted on a projection 207 of the casing of the looper and can be locked by the locking lever 211. For the purpose of exchanging the spool 209, the casing 193 of the looper is brought into the position represented in Fig. 12. By compressing the spring 212 by means of the levers 210 and 211, the locking of the holding finger 208 is released and the finger 208 can then be brought into the position shown in Fig. 13. A resilient push button is arranged in the casing 193 of the looper for the purpose of facilitating the pushing out of the spool. The housing 193 has a bore 213 for the reception of the pin 214 and the shuttle 194 has an opening 218 to receive the pin 215. The push button is pushed outwards by the compression spring 216. The pin 217, which engages in a corresponding slot, serves for limiting the movement of the push button. The pin 214 of the push button is moved inwards for the purpose of pushing out the spool. When this is being done, the pin 215 comes into action on the end wall of the small spool 209 through a hole 218 provided in the shuttle and pushes the spool 209 and the housing of the spool out of the shuttle. The spring 216 then brings the pin 214/215 back into its original position.

The construction according to Figs. 14 to 16 agrees with the construction according to Figs. 8 to 10 in so far as, in the two cases, the raising and lowering of the slide rod 121, which carries the thread-feeder roller 129, is effected from the rotating shaft 107 through the crank pin 109, the coupling 110, the rocking lever 112 and the rocking lever 121, the sliding block 124 of which engages in the slide rod 121. Further, in the case of both gearings, the pin 113 of the rocking lever 112 is arranged on an adjusting member 114 which is adjustably connected to the stand 115 of the machine with the aid of screws 116 and slots 117 for the purpose of altering the stroke of the slide rod 121.

Now, whereas, according to Figs. 8 to 10, the rocking lever 121 was connected to a rigid arm 123 of the stand of the machine, in the case of the gearing according to Figs. 14 to 16, the pivot pin 122 of the rocking lever is fitted to the crank arm 180 which is rigidly connected with the shaft 181. The shaft 181 is rockably mounted in the stand 115 of the machine and carries a lever arm 182 the roller 184 on which bears, under the action of the torsion spring 186, which surrounds the shaft 181, on the cam plate 185 which is connected with the shaft 107. The initial tension of the spring 186 can be regulated with the aid of a bush 187 which is rotatable in the stand of the machine and is fixable by a screw 189 and which has on one end a slot 187' for receiving the end 186' of the spring and has, on its other end, an hexagonal part 188 which serves as a handle. The set screw 191, on which the extension 190 of the lever arm 182 can bear, determines one end position of the shaft 181 and, consequently, of the crank arm 180.

On the upward movement of the thread-feeder roller 129—i. e., on the upward rocking of the lever 121, the cam roller 184 is located on the high part of the cam 185. The rocking shaft 181 then receives no movement and the extension 190 of the lever 182 bears on the stop screw 191. The pulling in of the thread loop, which has just been carried over the shuttle, is effected positively merely by 75 the coupling drive 109/121, since the parts 180 to

184 are kept stationary between the raised part of the cam 185 and the stop 191 and, consequently, the pin 122 remains stationary. The beginning of the downward movement of the lever 121 is represented in Fig. 14.

On the upward movement of the thread-feeder roller 129 (Fig. 7), the movement is delayed owing to the fact that the cam roller 184 is moved resiliently into the depression in the cam 185. Consequently, the pin 122 is moved upwards, the lever 121 is rocked about the pin 118 and the sliding block 124 is moved downwards. However, this relative downward movement of the sliding block 124 means only a delay in the downward movement of the thread-feeder roller which corresponds to the work of the auxiliary take-up otherwise provided. This movement takes place in the time in which the needle pulls the bottom thread loop out of the piece being sewn.

The cam 185 is arranged in such a manner that there is imparted to the pin 122 and, therefore, to the sliding block 124 and the thread-feeder roller 129 a movement which corresponds to the upward movement of the needle. In the sewing, the thread-feeder roller therefore necessarily releases exactly as much thread as the needle pulls out at any moment. If, however, during the sewing, a fairly large variation in the thickness of the piece being sewn occurs, this difference is compensated for in the stroke of the thread feeder by the ability of the additional gearing to yield resiliently. The spring 186 on shaft 181, as shown in Fig. 16, renders it possible for the roller 184 to raise resiliently from the cam disk 185 when the thread tension in roller 129 becomes too great. When the thread-feeder roller yields upwards, the sliding block 124 is moved upwards and the cam roller 184 is raised by the cam 185 in opposition to the tension of the spring.

After the loop has been pulled out by the needle, 40 the cam roller 184 is again moved on the cylindrical part of the cam 185 by the further rotation of the latter and the lever 182 is fixed between the stop 191 and the cam 185.

The additional movement that is effected from the shaft 181 therefore takes the place of the too slowly working resiliently acting auxiliary take-up 160 of the construction according to Figs. 8 to 10. It serves the purpose of releasing the thread in accordance with the movement of the needle in the time in which the needle takes the loop out of the piece being sewn and, further, of resiliently compensating for irregularities owing to the alteration of the thickness of the piece being sewn. Notwithstanding this, the pulling in of the thread loop is effected positively and with an adjustable size of stroke of the thread-feeder roller.

In the construction according to Figs. 17 to 19, a higher coupling drive is provided in the driving device for the slide rod 121 and between the driving crank pin 109 and the lever 121, which carries the sliding block 124 and rocks about the pin 122. Here, the crank pin 109 is embraced by an arm of a coupling 220, the other arm of which is connected to the link 222. The link 222 is rockably mounted on a pin 223 that is fixed in the body of the machine. The pin 224 of the coupling 220 is hinged to the coupling 225 which is connected, on the one hand, with the link 226 by the pin 227 and, on the other hand, with the rocking lever 121 by the pins 228 and 229 and the hinged link 229. The link 226 rocks about the pin 230 which is carried by the adjusting member 231 that

is fixed to the body of the machine by screws and slots.

Owing to the higher coupling drive of this construction, the result is obtained that the pin 224 of 5 the coupling 220 describes a cam movement on the movement of the said drive, which coupled curve prolongs the stoppage of the sliding block 124 and, consequently, of the thread-feeder roller 129 in the bottom end position. In this way, the 10 faultless pulling in of the thread on the formation of stitches is favoured. In addition, owing to the mounting of the hinge bolt 230 of the link 226 on the adjusting member 231, the possibility is here given of carrying out the alteration of stroke of 15 the thread-feeder roller which is to be effected on a variation in the thickness of the work piece, without shifting the top end position of the thread-feeder roller.

In the case of the constructions according to 20 Figs. 8 to 10 and 14 to 16, there is employed, for the purpose of altering the stroke of the thread-feeder roller 129, the adjusting member 114 to which the link 112 of the coupling 110 is connected. The result of an alteration of the position 25 of the adjusting member 114 is, in those cases, that, with the alteration of the size of the stroke of the thread-feeder roller, both the top and bottom end positions of the latter are altered. In contradistinction to this, if the adjusting member 30 231 of the construction according to Figs. 17 to 19 is shifted for the purpose of compensating for too great differences in the thickness of the piece being sewn, the pin 230 effects, when the coupling 226 (Fig. 17) is in the position which corresponds 35 to the top position of the thread-feeder roller, only a rocking of the link about the pin 227 without transmitting a movement to the coupling itself. The top end position of the thread-feeder roller therefore remains unaltered. A movement 40 of the adjusting member upwards produces, when the thread feeder is in the bottom position of rest (Fig. 18), a raised position of the link bolt 227 of the coupling 225, and, consequently, of the rocking lever 121 which is connected with the 45 coupling by the link 228. The alteration of stroke is therefore effected solely by shifting the bottom end position of the thread feeder. In this way, a uniformly deep pulling of the thread into the material of the work piece is ensured with every thickness of the work piece.

What I claim is:

1. A lock-stitch sewing machine of the type including a needle bar, shuttle, thread feeder, and a whirl, comprising a horn receiving the thread feeder and whirl, a rotary carrier for the horn, a tubular shaft in the lower end of the rotary carrier, a pinion on the lower end of the tubular shaft, an intermediate shaft journalled in the rotary carrier parallel to and spaced from 55 the axis of the latter, a pinion fixed on the lower end of the intermediate shaft and meshing with the first mentioned pinion, a gear mounted to revolve on a fixed axis parallel to the axis of the rotary carrier, said gear meshing with the 60 first mentioned pinion, a bevel gear below said last mentioned gear and having fixed relation thereto to revolve therewith, a drive shaft, and a bevel gear adapted to be driven from said drive shaft and meshing with the first mentioned bevel 65 gear.

2. A construction as defined in claim 1, including a thread clamp, two slide rods as operating linkages for the thread feeder and the thread clamp, a guide forming the axis of the 70 horn with said guide having two longitudinal

grooves to slidably receive the slide rods, the slide rod which operates the thread clamp being controlled by a cam.

3. A construction as defined in claim 1, including a thread clamp, two slide rods as operating linkages for the thread feeder and the thread clamp, a guide forming the axis of the horn with said guide having two longitudinal 15 grooves to slidably receive the slide rods, the slide rod which operates the thread clamp being controlled by a cam, the slide rod which controls the thread feeder being operated by a coupling drive wherein the coupling is formed with three corners, a driving crank pin connected to one corner, a sliding pin operating in a slot in a 20 rocking lever acting upon the slide rod engaging the second corner, and a rocking lever connected to the third corner, the rocking lever having a pivot pin carried by a sliding member adjustable on the casing to alter the stroke of the thread 25 feeder.

4. A construction as defined in claim 1, including a thread clamp, two slide rods as operating linkages for the thread feeder and the thread clamp, a guide forming the axis of the horn with said guide having two longitudinal 30 grooves to slidably receive the slide rods, the slide rod which operates the thread clamp being controlled by a cam, the cam controlling a bell-crank lever for acting upon the slide rod of the 35 thread clamp, with a set-screw to vary the vertical position of a projection on the slide rod to engage the thread clamp.

5. A construction as defined in claim 1, including a thread guiding roller mounted for rotation in a fixed axis of the horn, a movable thread clamp acting on the thread guiding roller, an elongated slide on which the thread clamp is mounted, means to permit axial movement of the slide in a direction varying from that of the 40 slide rod controlling it, and a spring which presses the slide and thread clamp to the guide roller.

6. A construction as defined in claim 1, including a heating device arranged within the rotatable horn carrier surrounding a rod guide for 45 heating the thread carried within the bore of the rod guide.

7. A construction as defined in claim 1, including a thread clamp, two slide rods as operating linkages for the thread feeder and the thread 50 clamp, a guide forming the axis of the horn with said guide having two longitudinal grooves to slidably receive the slide rods, the slide rod which operates the thread clamp being controlled by a cam, a rocking lever acting on the slide rod of the 55 thread feeder and having a pivot pin, a crank arm on which the pivot pin is mounted, with the said crank arm rocked in accordance with the sewing operation to thereby impart to the rocking lever and to the thread feeder an additional movement to compensate for the work of the ordinary conventional auxiliary take-up.

8. A construction as defined in claim 1, including a thread clamp, two slide rods as operating linkages for the thread feeder and the thread clamp, a guide forming the axis of the horn with said guide having two longitudinal 60 grooves to slidably receive the slide rods, the slide rod which operates the thread clamp being controlled by a cam, a rocking lever acting on the 65 slide rod of the thread feeder and having a pivot pin, a crank arm on which the pivot pin is mounted, with the said crank arm rocked in accordance with the sewing operation to thereby impart to the rocking lever and to the thread feeder an 70 75

additional movement to compensate for the work of the ordinary conventional auxiliary take-up, a rocking shaft on which the crank arm is pivoted, a second arm for rocking said shaft, and a cam plate for operating the second arm.

5 9. A construction as defined in claim 1, including a thread clamp, two slide rods as operating linkages for the thread feeder and the thread clamp, a guide forming the axis of the 10 horn with said guide having two longitudinal grooves to slidably receive the slide rods, the slide rod which operates the thread clamp being controlled by a cam, a rocking lever acting on the slide rod of the thread feeder and having a pivot 15 pin, a crank arm on which the pivot pin is mounted, with the said crank arm rocked in accordance with the sewing operation to thereby impart to the rocking lever and to the thread feeder an additional movement to compensate for 20 the work of the ordinary conventional auxiliary take-up, a rocking shaft on which the crank arm is pivoted, a second arm for rocking said shaft, and a cam plate for operating the second arm, and an adjustable spring for pressing the arm 25 yieldingly to the cam plate.

10 10. A construction as defined in claim 1, including a thread clamp, two slide rods as operating linkages for the thread feeder and the thread clamp, a guide forming the axis of the 30 horn with said guide having two longitudinal grooves to slidably receive the slide rods, the slide rod which operates the thread clamp being controlled by a cam, a rocking lever acting on the slide rod of the thread feeder and having a pivot pin, a crank arm on which the pivot pin is mounted, with the said crank arm rocked in accordance with the sewing operation to thereby impart to the rocking lever and to the thread feeder an additional movement to compensate for 40 the work of the ordinary conventional auxiliary take-up, a rocking shaft on which the crank arm is pivoted, a second arm for rocking said shaft, and a cam plate for operating the second arm, and an adjustable spring for pressing the arm 45 yieldingly to the cam plate, the cam plate being provided with a raised part for maintaining the crank arm of the rocking shaft and the pivot pin stationary during the downward movement of the thread feeder, said cam plate 50 having a depressed part acting on the upward movement of the thread feeder to impart to the rocking lever an additional movement in a direction to delay the normal upward travel of the thread feeder.

55 11. A lock-stitch sewing machine of the type including a thread feeder, a whirl, a reciprocal needle bar and a shuttle picker, and means for driving the shuttle picker, including a uniformly rotating crank, a three armed crank connected

to the uniformly rotating crank, a link connecting the pivot of the last mentioned crank to the machine, a follower, the connection compelling the follower to travel in a path approximating an 8-shaped loop, and a slide link provided with a cam groove and having its axis of rotation in one part of the 8-shaped loop, the follower being engaged in the cam-shaped groove of the link to transmit movement to the shuttle picker.

5 12. A construction as defined in claim 11, including a shaft carrying the slide link, means for supporting the shaft for rotation and for axial displacement, a second shaft in splined relation to the first shaft to revolve therewith, a 15 toothed wheel fixed on the second shaft, a shuttle drive including a gear meshing with said toothed wheel, and a carriage in which the shuttle drive is mounted, said carriage being displaceable transversely of the direction of sewing and 20 supporting the shuttle and the shuttle actuator, and means to effect movement of said carriage.

13. A construction as defined in claim 1, characterized by having a vertical rod guide provided with a longitudinal guide groove and having a thread feeder operating rod mounted in said groove and actuating the thread feeder, a bell crank lever, means to rotate the end of one arm of the lever through a circular path, a link having one end mounted on a fixed pivot and its other end pivoted to the end of the remaining arm, an operating lever having one end mounted on a pivoted support and its other end operatively connected to said operating rod, and a linkage connecting the angle of the bell crank 35 lever and the operating lever at a point intermediate its ends.

14. A construction as defined in claim 1, characterized by having a vertical rod guide provided with a longitudinal guide groove and having a 40 thread feeder operating rod mounted in said groove and actuating the thread feeder, a bell crank lever, means to rotate the end of one arm of the lever through a circular path, a link having one end mounted on a fixed pivot and 45 its other end pivoted to the end of the remaining arm, an operating lever having one end mounted on a pivoted support and its other end operatively connected to said operating rod, a second bell crank lever having one arm pivoted 50 to the angle of the first bell crank lever, a link connecting the angle of the second bell crank lever to the operating lever at a point intermediate its ends, an adjustable slide, a link connecting said slide to the remaining arm of the 55 second bell crank lever, and means to secure the slide in adjusted position.

EWALD KÜHN.
